101,291

DESIGN FOR AN UMBRELLA

Julian E. Schrader, New York, N. Y.

Application July 9, 1936, Serial No. 63,745

Term of patent 3½ years

To all whom it may concern:

Be it known that I, Julian E. Schrader, a citizen of the United States, residing in New York, county and State of New York, have invented a new, original, and ornamental Design for an Umbrella, of which the following is a specification, reference being had to the accompanying drawing, forming a part thereof.

In the drawings—

Fig. 1 is a plan view of an umbrella illustrating my new design.

Fig. 2 is an elevational view thereof.

I claim:

The ornamental design for an umbrella substantially as shown.

JULIAN E. SCHRADER.
